WILLIAM DIETER, OF BROOKLYN, NEW YORK.

TORPEDO AND SUBMERGED LAUNCHING-TUBE.

1,316,284.

Specification of Letters Patent. Patented Sept. 16, 1919.

Application filed January 25, 1919. Serial No. 278,131.

To all whom it may concern:

Be it known that I, WILLIAM DIETER, a citizen of the United States of America, residing in the borough of Brooklyn, city and 5 State of New York, have invented certain new and useful Improvements in Torpedoes and Submerged Launching-Tubes, of which the following is a specification.

This invention relates to torpedoes and 10 launching means therefor, for use chiefly in connection with submarines or submersible boats, although useful also on battleships or other craft where the submergence of the launching tube may vary. The object of the 15 invention is to maintain a balance of air pressure within the torpedo and within the launching tube up to the moment of launching, notwithstanding the varying hydrostatic pressure due to the varying depths of 20 submergence of the tube.

The preferred embodiment of the invention is shown in the accompanying drawings, wherein—

Figure 1 is a diagrammatic view, being 25 a longitudinal vertical section, on a small scale, of the fore part of a submarine, with its launching tube and torpedo, the latter shown in elevation;

Fig. 2 is a section on the same plane, of a 30 fragment of the launching tube and torpedo, showing their connections;

Fig. 3 is a vertical longitudinal mid section of the air pressure regulator;

Fig. 4 is a horizontal section of the latter, 35 on a smaller scale.

Referring to Fig. 1, A designates the hull of a submarine, B the launching tube, and C the torpedo. D is the air pressure regulator as a whole, and E is a source of compressed air, such as a reservoir or flask, into 40 which compressed air is pumped from any suitable compressor.

It is impracticable to construct torpedoes so that water will be excluded from the afterbody under abnormal pressures, that is, pressures below the deepest depth of immersion at which the torpedo is designed to run. Consequently, when a torpedo is in the torpedo tube of a submarine, and the 45 latter dives to a greater depth, the water entering the launching tube under pressure forces its way into the afterbody of the torpedo. The water thus entering constitutes ballast, which, if the torpedo were launched 50 in this condition, would destroy its sub-

mersion balance and would have other disadvantageous results. For example, the water would be liable to enter through the turbine nozzles into the superheater, and might prevent the ignition of the superheating charge upon launching. Efforts to exclude the water from the launching tube have been unsuccessful.

According to my invention, the water is excluded from the afterbody of the torpedo 60 by maintaining therein an air pressure so nearly balancing the pressure surrounding the torpedo, that is, the pressure within the launching tube, as to effectually prevent the water being forced into the torpedo. To 65 this end the afterbody of the torpedo is connected to a source of compressed air through the medium of pressure-controlling mechanism, whereby as the pressure within the launching tube increases, compressed air is 70 introduced into the afterbody so as to maintain a substantially equal pressure therein; and conversely, as the pressure in the launching tube falls, the excess pressure in the afterbody is discharged, so that the 75 pressures within and exterior to the torpedo are kept substantially balanced.

To accomplish this result it is necessary to connect the afterbody of the torpedo directly or indirectly with the pressure regulator D, and also to connect this regulator with the interior of the launching tube. The latter connection may be permanent, but the former must be of such nature as will be severed upon the launching of the 80 torpedo. Disregarding for the moment the details of such separable connection, it is sufficient to state that a tube or conduit F connects at one end to the interior of the afterbody, and at the other end to the shell 85 of the pressure regulator, while from the latter a tube or conduit G connects to the interior of the launching tube. The regulator D is of such construction as to respond to differences of pressure transmitted to 90 it through the tubes F and G, and to compensate therefor by admitting pressure from the reservoir E, or escaping pressure to the atmosphere, according as the pressure in the torpedo afterbody is lower than, or higher 95 than, that in the launching tube.

The regulator D may be variously constructed, but a suitable construction is that shown, wherein the shell or casing H is divided by a partition I to form two chambers J and 100

K, the former connecting through F with the torpedo, and the latter connecting through G with the launching tube; in the partition I are mounted two diaphragms, 5 L and M, in such manner that they are exposed to the pressures in the chambers J and K, so that they will be displaced by a preponderance of pressure in either chamber. The diaphragm L operates a valve N 10 which controls the flow of compressed air from E through conduit O, into the chamber J, and thence into the torpedo. The diaphragm M operates a relief valve P which controls the escape of surplus air from the 15 chamber J to the exterior of the casing, that is to say, into the hull of the submarine.

In operation, let it be assumed that the submarine has been on the surface, so that 20 the hydrostatic pressure in the launching tube is so nearly normal as to be negligible. If thereupon the submarine submerges, the hydrostatic pressure in the tube proportionately increases, whereas at first that within 25 the torpedo is unaltered. This gives rise to an unbalanced pressure within the regulator; that is to say, the pressure in chamber K exceeds that in chamber J, and consequently the diaphragms L, M are dis- 30 placed toward J. The displacement of M in this direction has no result; but the displacement of L acts to open the valve N and permit compressed air to enter from O into J, and thence to escape through F into the 35 torpedo; this flow continues until the pressures in K and J are substantially equalized, whereupon the diaphragm returns to normal position, the valve N closing (preferably with the pressure) and shutting off the 40 inflow of compressed air. By this means compressed air is introduced into the after- body to a pressure nearly or substantially equaling the hydrostatic pressure in the launching tube, so that if (as is usual) wa- 45 ter is contained in the launching tube, it is prevented from flowing therefrom into the torpedo. If now the submarine rises to a higher level or broaches to the surface, the hydrostatic pressure in B correspondingly 50 diminishes, whereupon the preponderant pressure in the torpedo communicated to the chamber J, gives rise to an opposite unbalanced pressure condition, whereby the dia- phragms L, M are displaced in the contrary 55 direction. Such displacement of L is with- out result; but the displacement of M opens the relief valve P and permits compressed air to flow out from J into the submarine 60 hull, an effect which continues until the pres- sures in J and K are substantially equalized. Thus, the excess air is discharged from within the torpedo and delivered into the submarine, where it is not wasted, but is utilized as part of the air supply for maintain- 65 ing respiration by the crew.

It will be understood that various constructions of diaphragms or equivalent pressure-responsive elements, and of valves operated thereby, and various constructions for connecting the conduit F to the torpedo, 70 may be provided, within the scope of the present invention, it being immaterial, in a broad sense, what constructions in detail are employed, so long as the essential operations thus described are performed. To enable those skilled in the art to more readily practice the invention, a description will now be given of the details of construction in the preferred embodiment shown, it being understood that the invention, in its 80 broader aspect, is not limited thereto.

Referring to Fig. 2, the conduit F comprises a tube a (which may be a flexible tube) from the regulator D to the launching tube, and within the launching tube preferably comprises a flexible tube or hose b connected at one end to the terminus of the tube a, and at the other to a pull-out connection or nozzle c, which effects communication with the interior of the afterbody, the air entering the latter through an outwardly-closing check valve d pressed to its seat e by a spring f. The air entering from tube b passes through the hollow nozzle c (having a shoulder which makes a packed joint with the gasket located at g), and through air passage h and through the valve seat, and thence through a tube i into the afterbody. The nozzle c has a shoulder j which, when seated, is engaged by a spring or springs k for maintaining the connection. It is necessary to hold the valve d open while this connection is maintained, in order to avoid any obstruction to the inflow or outflow of compressed air, and this function 105 is conveniently performed by the nozzle c acting against the stem of the valve d so as to hold the valve unseated against its spring stress. This condition continues until the admission of pressure to the launching tube 110 for ejecting the torpedo, whereupon, in the first part of the launching movement of the latter the hose b is pulled taut, whereupon the nozzle c remains stationary while the torpedo is moving outward, and the nozzle 115 releases itself from the grip of the springs k and consequently disconnects itself from the torpedo. Instantly thereupon the valve d is closed by its spring, so that inflow of sea water to the torpedo is avoided.

The pressure regulator D requires essentially one or more movable pressure-responsive elements for operating the respective valves. While one such element would suffice, it is preferable to employ two, one 125 for each valve. Diaphragms are the most practical form of such elements. In the construction shown, the diaphragm L is connected by a stem l, and through a push-piece m, to the valve stem n of the valve N, which 130

latter has a spring *o* tending to seat it. It results from this that the displacement of the diaphragm *L* toward the chamber *J* is utilized to push open the valve *N*, while the displacement of the diaphragm in the contrary direction has no effect after the valve *N* is seated.

The connection between the diaphragm *M* and valve *P* is to contrary effect. The connection between diaphragm stem *p* and valve stem *q* is essentially a pull connection. As shown, it is constituted by a wire link *r* engaging elongated holes or slots in the respective valve stems, these slots having sufficient play to permit the unobstructed maximum movement of the diaphragm toward chamber *J*. When the pressures are balanced, the parts *p*, *r*, *q* engage, so that upon the displacement of the diaphragm toward *K*, the valve *P* is pulled open and compressed air escapes from *J* to the exterior. The valve *P* is seated by a spring *S* engaging its valve stem.

While the conduit *F* might connect with any part of the afterbody, the special arrangement shown has an important function not thus far stated. When water finds entry into the afterbody, as may sometimes happen, it is desirable to have some means (analogous to a bilge pump) for expelling such water. This is accomplished by the construction shown, by reason of the tube *i* being extended down to a low part of the afterbody, so that its end is sealed in any such bilge water. Then, when the outflow of excess pressure from the afterbody takes place, the water is forced out by the air pressure above it, and the water, entering the lower chamber of the regulator, escapes therefrom by the valve *P*. The emission of water shows the operator what is the condition within the afterbody. When all excess water has been expelled, it is followed by a discharge of air. To direct the outflowing water downward, it is advantageous to provide an outer tubular shield *u*.

I claim as my invention:—

1. The combination with a torpedo and launching tube, of a source of compressed air, and means responsive to differences in pressure within the torpedo and within the launching tube adapted to feed compressed air from said source into the torpedo when the pressure in the latter falls materially below that in the tube.

2. The combination with a torpedo and launching tube, of a source of compressed air, and means responsive to differences in pressure within the torpedo and within the launching tube adapted to discharge from the torpedo pressures materially in excess of those in the tube.

3. The combination with a torpedo and launching tube, of a source of compressed air, and means responsive to differences in

pressure within the torpedo and within the launching tube adapted to control the flow of compressed air into and from the torpedo, whereby to maintain such pressures approximately equal.

4. The combination with a torpedo and launching tube, of a source of compressed air, a pressure regulator and conduits connecting it respectively with the interior of the torpedo, the interior of the tube, and with said source, said regulator including a pressure-responsive element and valves adapted to control the flow of compressed air into and from the torpedo, whereby to maintain approximately equal pressures within the torpedo and tube.

5. In apparatus according to claim 4, the pressure regulator comprising a casing divided into chambers, the pressure-responsive element exposed to the pressures in such chambers respectively, and valves operated thereby controlling the flow of compressed air from said source to the torpedo, and from the torpedo to the exterior.

6. In apparatus according to claim 4, the pressure regulator comprising a casing divided into chambers, diaphragms exposed on opposite sides to the pressures in said chambers respectively, and valves operated by the respective diaphragms, the one valve controlling flow of compressed air from said source to the torpedo, and the other valve controlling escape of air from the torpedo to the exterior.

7. In apparatus according to claim 1, a conduit connecting the torpedo afterbody with the pressure-controlling means, comprising a separable connection with the torpedo.

8. In apparatus according to claim 1, a conduit connecting the torpedo afterbody with the pressure-controlling means, and a valve controlling the communication between such conduit and the interior of the torpedo, adapted to be unseated while the connection is maintained, and to close such communication upon the launching of the torpedo.

9. In apparatus according to claim 1, the torpedo having an opening through which compressed air enters it, and a valve adapted to close said opening when the torpedo is launched.

10. The combination with a torpedo, of a source of compressed air, a conduit leading from the lower part of a chamber within the torpedo to the exterior, and means for introducing compressed air into said chamber whereby to discharge bilge water from said chamber through said conduit.

11. In apparatus according to claim 2, a conduit leading from the lower part of a chamber within the torpedo whereby the discharge from the torpedo expels bilge water from said compartment.

12. In apparatus according to claim 4, a conduit leading from the lower part of a chamber within the torpedo to said regulator, whereby to expel water from said chamber into the regulator, and the latter having an outlet valve on its lower side to discharge such water.

13. In apparatus according to claim 12, said outlet valve having means for directing downwardly the outflowing water. 10

In witness whereof, I have hereunto signed my name.

WILLIAM DIETER.
